(57) **CLAIM**

The ornamental design for stacked golf balls secured by transparent film to a flat base, as shown and described.

DESCRIPTION

FIG. 1 is a perspective view of stacked golf balls secured by transparent film to a flat base showing my new design; FIG. 2 is a front view thereof; FIG. 3 is a left side view thereof; FIG. 4 is a rear view thereof; FIG. 5 is a right side view thereof; FIG. 6 is a bottom view thereof; FIG. 7 is a top view thereof; and, FIG. 8 is a section view thereof taken along line 8-8 in FIG. 1.

The broken lines shown represent unclaimed subject matter and form no part of the claimed design.

The long dash-short dash-short dash lines represent an unclaimed boundary that forms no part of the claimed design.

1 Claim, 5 Drawing Sheets
